UNITED STATES PATENT OFFICE.

GEORGE W. CONLEY, OF WHEATON, ILLINOIS.

SMOKER'S STAND.

1,278,597.

Specification of Letters Patent. Patented Sept. 10, 1918.

Application filed April 16, 1917. Serial No. 162,426.

To all whom it may concern:

Be it known that I, GEORGE W. CONLEY, a citizen of the United States, residing at Wheaton, in the county of Dupage and State 5 of Illinois, have invented certain new and useful Improvements in Smokers' Stands, of which the following is a specification, reference being had to the accompanying drawings.

10 This invention relates to ash and cigar receivers, and particularly to a smoker's stand designed to receive ashes and cigar stumps.

One object of this invention is to provide a relatively large hollow base designed to 15 receive ashes and other refuse, and to provide a top for the base having an aperture, as stated, and providing in connection therewith a rotatable bowl shaped member which, in one position, closes said aperture, and in 20 another position discloses the aperture, the top having interlocking engagement with the base.

Other objects will appear in the course of the following description.

25 My invention is illustrated in the accompanying drawings, wherein:—

Figure 1 is a fragmentary vertical sectional view of my improved stand; and Fig. 2 is a top plan view thereof.

30 The base of the stand, which is designated 10, is preferably made of metal and is hollow and is enlarged at its bottom so as to provide for sufficient stability. This hollow base 10 is open at the top and may be circular in cross section, octagonal, or any other desired form and, of course, may be made extremely ornamental. Closing the upper 35 end of the base is a top, designated 11 and preferably this top is somewhat bowl shaped or conical in form, and is provided with an eccentrically disposed opening 12. Extending 40 downward from the top 11 and formed integral therewith and concentric to the central opening, is an annular sleeve 13, which fits within the base 10, and has telescopic engagement therewith, and preferably the base 10 is formed with bayonet slots 14 and the sleeve 13 has outwardly projecting pins 15, adapted to engage in said bayonet slots so

45 that in order to connect the top 11 to the base, the pins 15 are inserted within the bayonet slots and then the top is rotated a

partial rotation to engage the pins with the horizontal portions of the bayonet slots.

Extending transversely across the sleeve 55 13, below the lower end of the opening 12, is a deflector 16, which is attached to the sleeve 13 at its ends and is transversely V-shaped so that any ashes, trash, etc., which is discharged through the opening 12 will be 60 deflected into the interior of the base 10, but if the base 10 should be overturned accidentally, this deflector 16 will hinder the ashes from being discharged through the opening 12. Disposed within the bowl-shaped body is a bowl-shaped member 17 which is pivoted to the body at its center, and which is provided with an opening 18. With this construction, when the member 17 is rotated to one position, the openings 18 70 and 12 will be out of register and, as a consequence, the effluvia from the half smoked cigars, ashes, etc., cannot pass upward from the base, but the member 17 may be shifted from time to time, so as to bring the openings 12 and 18 into registry to permit ashes to be discharged into the base. 75

Now it is obvious that the base 10, which may be made of any desired diameter and of any desired height, is adapted to contain 80 a relatively large amount of ashes, etc., so that it need not be emptied for days, or even weeks, but when the base becomes filled, or it is desired to empty it for any other reason, it is only necessary to disengage the top 85 from the base and discharge the contents of the base.

It will be obvious that the top may be readily disengaged from the stand 10 so as to discharge the ashes from the stand and so 90 as to permit the top to be thoroughly cleaned. The deflector 16 will tend to impede the discharge of ashes from the stand 10 if the latter should be accidentally overturned and the hollow stand will prevent accidental disengagement of the top from the stand, if the stand be overturned, or if the stand be lifted by its top.

Having described my invention, what I 100 claim is:—

A smoker's stand comprising a hollow base forming a receptacle, a bowl shaped top greater in diameter than the base and hav-

ing a sleeve integral therewith and snugly fitting in the upper end of said base, the top having an opening disposed eccentrically to the top and a bowl shaped member fitting 5 snugly upon and within the bowl shaped top and pivotally mounted at its center to the bowl shaped top for rotation, and having an aperture adapted to be brought into register with the aperture on the bowl shaped top

and having a handle whereby it may be rotated.

In testimony whereof I hereunto affix my signature in the presence of two witnesses.

GEORGE W. CONLEY.
